VEHICLE MARKER LIGHT LENS

George A. Knapp, Syracuse, N.Y., assignor to R. E. Dietz
Company, Syracuse, N.Y.

Filed Nov. 2, 1970, Ser. No. 25,788

Term of patent 14 years

Int. Cl. D26—06

U.S. Cl. D48—32

FIG. 1 is a top plan view of a vehicle marker light lens embodying my new design;

FIG. 2 is a cross-sectional view taken on line 2—2 of FIG. 1;

FIG. 3 is a bottom plan view thereof; and

FIG. 4 is an end elevational view thereof, the interior configuration being omitted for convenience of illustration.

I claim:

The ornamental design for a vehicle marker light lens, substantially as shown and described.
